UNITED STATES PATENT OFFICE.

ELIAS F. YOUNCE, OF UNION, OHIO.

SILO.

1,001,724.

Specification of Letters Patent. Patented Aug. 29, 1911.

Application filed December 13, 1910. Serial No. 597,075.

To all whom it may concern:

Be it known that I, ELIAS F. YOUNCE, a citizen of the United States, residing at Union, in the State of Ohio, have invented 5 certain new and useful Improvements in Silos; and I do declare the following to be a full, clear, and exact description of the invention, such as will enable others skilled in the art to which it appertains to make and 10 use the same, reference being had to the accompanying drawings, and to the letters and figures of reference marked thereon, which form a part of this specification.

This invention relates to new and useful 15 improvements in silos.

One object of the invention is to provide a silo that may be erected without the aid of skilled labor.

Another object of the invention is to provide 20 an improved form of door which allows easy access to the interior of the silo. The doors are not detachable or removable from the silo when opening them. This avoids 25 the possibility of their being misplaced about the premises. The easy manipulation of said doors is a feature of the improvements which I desire to emphasize.

Referring to the drawings, Figure 1 is a front elevation of my improved silo. Fig. 2 30 is a front elevation of one of the doors. Fig. 3 is a section on the line *a—a* of Fig. 2. Fig. 4 is a section on the line *b—b* of Fig. 2; and Fig. 5 is a perspective view of a portion 35 of the door construction on the line *c—c* of Fig. 2.

Throughout the specification and drawings, similar reference characters indicate corresponding parts.

Mounted on a base 1 is a plurality of 40 panels 2 which are placed in circular form and are held in position by means of hoops 3 in a well known manner. The silo thus formed may be of any diameter or height, and the same is provided with the usual 45 conical roof 4.

To gain access to the interior of the silo at the various levels, depending upon the amount of fodder within it, a series of doors 50 extending along the entire side of the silo is provided as follows: The staves 2 are omitted from a portion of the circumference of the silo to provide an opening throughout its length, in which the doors are placed. Mounted on each side of this opening and 55 in alinement with the panels 2, are right and

left door jambs 5 which extend the entire length of the opening. Attached to the jambs 5 and held in alinement therewith by means of dowels 7, are strips 8. These strips are held apart by means of distance 60 pieces or struts 9, which are formed of angle bars. The horizontal portions of the angle bars 9 are cut away at their ends to allow the end vertical portions to lie between the jambs 5 and the strips 8, where they may be 65 attached in any convenient manner. This arrangement allows the ends of the horizontal portion of the angle bars to abut against the strips 8 where they are in a position to receive the strain and prevent the door opening 70 when the hoops 3 are tightened. As will be seen from Fig. 5, the hoops 3 pass through the strips 8 and under the horizontal portion of the angle bars.

The doors 10 are rectangular in shape, 75 and may be formed of a series of horizontal strips fitted by tongues and grooves and held together by battings 11. The vertical edges of the said doors are of wedge shape to conform with the angular edges 12 of 80 the door jambs 5, see Fig. 5. This construction allows the doors and jamb to form an air tight joint when the door is pressed outwardly by the fodder or other material on the interior of the silo. The upper and 85 lower horizontal edges 13 of the doors are inclined inwardly and downwardly to allow the lower edge of the upper door to abut against the upper edge of the lower door. This arrangement also forms a tight 90 joint between the doors, and owing to the direction of the incline, the moisture or juices deposited on the inner sides of the silo by the fodder will be prevented from seeping to the outside. The outer horizontal 95 and vertical edges of the doors may be provided with insulating material 14 such as felt, which engages the strips 7 and the vertical portion of the angle bars 9 respectively. The insulating material 14 insures 100 an air tight joint at the edges of the door in addition to the angular edges. As the side edges of the doors are on an angle, their width is greater than the door opening, and to enable the doors to be opened outwardly, said doors are provided each with 105 a hinge which allows said doors to be swung inwardly and then rotated on a central pivot and swung outwardly with the horizontal edges lying vertical. These hinges 110

are each constructed as follows: Mounted at a central point of the door, and on the outside, is a plate 15 attached to each door by means of a bolt 16. The plate 15 is provided with a shoulder or inner ridge which receives a ring or pivot member 17, and in which said plate is adapted to rotate. The ring 17 is provided with arms 18 which are hinged at 19 to arms 20. The arms 20 are hinged at 21 to one of the strips 8, and said hinge 21 is so placed as to allow the arm 20 to swing inwardly. After the foder has been removed from any door and it is desired to open such door, the said door is pressed inwardly and is given a 15 quarter turn on the ring 17. This brings the normal horizontal ends to a vertical position. One end of the door is then swung around through the door opening, which 20 allows the entire door to be extracted, as is shown in dotted lines in Fig. 3.

I claim as my invention:

1. The combination with a silo having an opening, of a door for said opening, arms 25 constituting a double hinge member between the silo and the door and upon which said door is movable on the interior and exterior of the silo, and a pivotal connection between the door and said double hinge 30 connection, whereby the door is first movable on the interior and then on the exterior of the silo, substantially as specified.

2. The combination with a silo having a door opening, and door jambs on the sides of said opening, of a door adapted to swing 35 inwardly from said opening and outwardly through said opening, a double hinge member connecting said door on one side, and a pivot member connecting said door with said hinge member; whereby said door may 40 be moved inwardly on said hinge, then partially rotated on said pivot and extracted through said opening, substantially as specified.

3. The combination with a silo having an 45 opening with door jambs on the sides thereof, of a door adapted to close said opening and engage said jambs, arms 20 connected to one of said door jambs by separate hinges 21, and to the door by a common hinge 19, a pivot member 15 connected with said arms 20 by the hinge 19, and upon which the door may be turned, a pivot 16 connecting said pivot member 15 and the door, whereby the said door may be moved inwardly 50 and then partially rotated and then moved on the exterior of the silo, substantially as specified.

In testimony whereof I affix my signature, in presence of two witnesses.

ELIAS F. YOUNCE.
